DESK

Giacomo Jack Buzzitta, Grand Rapids, Mich., assignor to Stow & Davis Furniture Company, Grand Rapids,
Mich., a corporation of Michigan

Filed Oct. 5, 1959, Ser. No. 57,795

Term of patent 14 years

(Cl. D33—7)

FIG. 1

FIG. 2

Fig. 1 is a perspective front view of a desk showing my new design.

Fig. 2 is a perspective rear view thereof.

Fig. 3 is an enlarged fragmentary view of an end portion of my new desk showing a partially sectioned part thereof.

Fig. 4 is a cross-sectional view of one of the legs thereof taken along the plane IV—IV of Fig. 3.

I claim:

The ornamental design for a desk, substantially as shown.
